UNITED STATES PATENT OFFICE.

WINFRED B. HOLTON, OF INDIANAPOLIS, INDIANA, ASSIGNOR TO THE
KEYLESS LOCK COMPANY, OF SAME PLACE.

KEYLESS LOCK.

SPECIFICATION forming part of Letters Patent No. 597,080, dated January 11, 1898.

Application filed August 5, 1897. Serial No. 647,229. (No model.)

To all whom it may concern:

Be it known that I, WINFRED B. HOLTON, a citizen of the United States, residing at Indianapolis, Marion county, State of Indiana, 5 have invented certain new and useful Improvements in Keyless Locks, of which the following is a specification.

My invention relates to permutation or combination locks, and, while it is applicable 10 to locks of various kinds, it is designed more especially for such locks as are adapted to be applied to lock-boxes, drawers, desks, and similar articles.

My present invention has for its object to 15 provide a self-locking combination or permutation lock—that is, a lock of the general character described which will automatically lock itself after it has been operated to open the box, drawer, or other article to which it 20 is connected, so that it cannot be surreptitiously opened by unauthorized persons; and to these ends my invention consists in the features of construction and arrangement, substantially as hereinafter more fully set 25 forth.

In the accompanying drawings, Figure 1 is 30 a side view of the operating mechanism of a lock of this general character sufficient to illustrate my invention. Fig. 2 is a similar view showing the bolt in its unlocked position, and Fig. 3 is a similar detail view showing another position of the parts.

As my invention is adapted to be applied 35 to various constructions of permutation or combination locks, I have not deemed it necessary to show the details of construction further than is desirable in illustrating the construction and operation of my improvements, as this will be sufficient to enable those skilled 40 in the art to make and use my invention and apply it to different forms of locks.

In the drawings, A represents the lock-plate of a well-known style of lock of this general character, the inclosing plate or case 45 being removed for clearness. On the face of the lock-plate are arranged some sort of dials or indicating devices by which the tumbler or tumblers of the lock can be manipulated, and means are also arranged, as usual, for 50 moving the latch, none of which are shown

herein, as they are independent of my present invention.

Mounted on the lock-plate A is a latch-plate B, which is of a well-known construction and is arranged to slide on the lock-plate, 55 being guided in the present instance by its upper end passing through an opening in the upturned portion A' of the lock-plate and its rear portion being slotted at B' to embrace a stud A², secured to the lock-plate. Any other 60 well-known or desirable form of lock-plate can be used of course, and in the present instance I have shown it as provided with two dogs or fingers adapted to coöperate with the tumblers or wheels in the manner hereinafter set 65 forth.

Mounted to move with the lock-plate is a latch C, its upper end passing through a slot in the lock-plate and its stem portion C' passing through an opening in the stud A², and a 70 spring C² surrounds the stem and tends to project the latch. There is a knob C³ connected to the latch which permits its operation from the inside, and of course there is some means (not shown) for moving the latch 75 from the outside when the lock is set at the proper combination. It will be understood that from the inside the latch can be moved without moving the latch-plate; but from the outside the latch can only be moved by first 80 moving the latch-plate, which plate is controlled in its movements by the tumblers or wheels.

Mounted on the lock-plate are the tumbler or tumblers or wheels D D, two being shown 85 in the present instance, and these are secured on pivots D' in any suitable and well-known manner, so that they can be turned in connection with any dial or other indicating device on the outside of the lock at any desired 90 or prearranged position. The peripheries of the tumblers may be notched, as shown in the drawings, or otherwise arranged, and at some point they are provided with a slot d. Usually this has been arranged as a radial slot, 95 so that when the tumblers are under the dogs or fingers b on the latch-plate upon the movement of the latter the dogs will pass into the slots directly, and on releasing the latch or latch-plate they will move out again into their 100

normal position. It will be understood that with this construction, if the operator of the lock should go away, leaving the tumblers in a position to allow the lock to be operated, 5 unauthorized persons could manipulate it, and it is to provide against such inadvertence or accident on the part of the operator that my present invention is made, and I do this by providing automatic devices which will 10 move the tumblers into the locking position when the latch or latch-plate is released.

In the present instance the slots *d* are made with an inclined or beveled side, so that this side does not extend radially into the body of the tumbler. In this way when the tumblers are arranged in unlocking position and the latch-plate is operated the dogs, entering the slots, tend to rotate the tumblers a short distance out of the normal or unlocked position. 15 Arranged on the tumbler or tumblers adjacent to the slots is a stop or trip *E*, which may be of any desired shape, and in the present instance is pivoted to the tumbler at *e*, and is normally held against the stop-pin *e'* by a spring *F*, also secured to the tumbler. The free end *E'* of the trip normally extends part 20 way over the slots *d*, as shown in Fig. 1, permitting the dogs or fingers *b* to enter the slots of the tumblers. As the dogs are pressed downward they come in contact with the inclined side of the slots *d*, rotating the tumblers, and the stop or trip *E* yields under the 25 operation of the dogs, so that it assumes a position substantially as shown in Fig. 2. When the latch is released and is projected to its normal position, the trip *E*, under the force of the spring *F*, assumes its normal position and comes under the dogs or fingers *b*, as 30 shown in Fig. 3, so that any attempt to operate the lock by unauthorized persons would result in the dog or dogs *b* impinging upon the end *E'* of the trip or stop *E*, preventing the dogs entering the slots *d*, and consequently 35 the operation of the lock. Of course it will be understood that an authorized person can move the tumblers so as to bring the open portion of the slots again in proper position, but the uninitiated or unauthorized person would not know how to move the tumblers to 40 permit the operation of the lock.

From this description the general construction and arrangement of the parts of my invention will be clearly understood, as well as

its mode of operation, and it will be seen that by the use of an exceedingly simple and inexpensive structure I provide an effective automatic self-locking combination-lock which is not liable to get out of order and which adds largely to the safety of the lock and renders its unauthorized operation more difficult.

What I claim is—

1. In a permutation or combination lock, a tumbler, provided with a slot having an inclined face, a dog adapted to enter the slot and make contact with the inclined face thereof, and means for preventing the reentrance of the dog, when the tumbler has been moved, substantially as described.

2. In a permutation or combination lock, a tumbler provided with a slot adapted to enter the slot of the tumbler, and a trip arranged on the tumbler adjacent to the slot and adapted to prevent the reentrance of the dog, substantially as described.

3. In a permutation or combination lock, the combination of a tumbler provided with a slot, having an inclined side and a pivoted trip on the tumbler, of a dog adapted to engage the inclined side on the trip according to the position of the tumbler, substantially as described.

4. In a permutation or combination lock, the combination of a tumbler provided with a slot and a spring-actuated trip arranged on the tumbler adjacent to the slot, and a dog adapted to engage the slot on the trip according to the position of the tumbler, substantially as described.

5. In a permutation or combination lock, the combination with the latch and dog, of a tumbler having a slot provided with an inclined side and a pivoted trip arranged adjacent to the slot whereby when the dog is operated the tumbler is partially rotated and when the dog is released the trip automatically moves into position to prevent its entering the slot, substantially as described.

In testimony whereof I have signed my name to this specification in the presence of two subscribing witnesses.

WINFRED B. HOLTON.
